UNITED STATES PATENT OFFICE

JOHN DAVENPORT SIDDELEY, OF COVENTRY, ENGLAND

MIXING DEVICE

Application filed February 2, 1927, Serial No. 165,403, and in Great Britain March 23, 1926.

This invention relates to internal combustion engines having a central crankcase and stationary cylinders arranged radially around it, and it has for its object to provide an effective means for supplying mixture to the cylinders, preferably from a single carburettor and at a slight pressure above atmospheric, although this is not essential. The chief difficulty with induction systems of this kind is to ensure equal distribution to the radially-arranged cylinders, and an even mixture.

The invention relates to a system involving an annular channel with radial, or approximately radial, pipes leading to the cylinders, and a centrally arranged branch to which the carburettor is connected.

In the accompanying drawings,

Figure 1 is an axial section of the induction system showing also a part of the engine crank chamber to which it is attached, and

Figure 2 is an incomplete section on the line II-II of Figure 1.

In the construction illustrated, one end plate 2 of the crank chamber 3 is provided with an overhanging flange 4 which forms the outer wall of an annular chamber 5, and this flange is formed with elbows 6 which are connected by radial, or approximately radial, pipes 7 to the various cylinders.

Bolted to this end plate 2 is a cover 8 so shaped as to form the annular chamber 5 from which the elbows 6 lead off. This cover, starting from the outer edge, therefore is so shaped as first to approach at 9 the crank chamber end plate 2, leaving there a narrow annular gap at 90 of, say, half an inch from the end plate 2. It then sweeps outwards as at 10 away from the end plate 2 and towards the axis O—O of the engine so as to form a conical chamber 11 communicating through the aforementioned gap with the annular one 5. The cover 8 is formed with a branch 12, preferably downwardly directed, to which the carburettor 13 is attached. Thus there is formed between the end plate 2 and the cover 8 an outer annular chamber 5 communicating through the gap with an inner, roughly conical chamber 11, forming a

connection between the annular chamber 5 and the carburettor attachment.

In the connecting chamber 11 and along the axis O—O of the engine is a revolving spindle 14 which may be driven directly or indirectly from the crankshaft 15, forming part of the latter in the present example, and this spindle carries fan blades 16 which lie chiefly in the largest part of the connecting chamber 11, and are formed on a flange 17 or disc 17, the hub 18 of which is fixed to the spindle 14 by a locking device such as 19. The outer ends of these blades, however, project beyond the edge of the disc 17 and extend into, and as far as possible fit the section of, the annular chamber 5.

The inner ends 160 of the alternate blades may be inclined at angles to the rotational axis differing from those of the adjacent blades to improve the flow of air between them.

Mixture is therefore drawn into the engine cylinders from the carburettor 13 through the conical connecting chamber 11, annular chamber 5, and radial inlet pipe 7, and equal distribution is effected by the particular arrangement and shape of the fan chamber and fan, which, in addition, prevents deposition of the fuel and thereby ensures a uniform mixture to all the cylinders. If the fan is geared up it may also cause the mixture to be supplied at a pressure slightly above atmospheric, but this is not essential.

If desired, a light spindle 20 may extend coaxially with the fan spindle 14 and be supported by a bearing 21 in the cover 8. If gearing is used for driving the fan, this spindle 20 may serve for its support and/or for connection to accessories or other parts beyond the cover 8.

What I claim as my invention and desire to secure by Letters Patent of the United States is:—

1. In a mixer for an induction system for a radial cylinder internal combustion engine, the combination of an annular chamber provided with a narrow annular inlet and outlet pipes spaced around the said chamber, a centrally arranged conical chamber communicating at its enlarged end with the annular chamber.

ber through the annular inlet, a carburetor connected with the small end of said conical chamber, a centrally revolving spindle carrying fan blades which lie chiefly in the annular cylinder and so constructed as to sweep out the whole of said annular chamber and the large end of the conical chamber.

5 2. The mixer as claimed in claim 1, having a continuation of the outer wall of the annular chamber contoured to form also the outer wall of the conical chamber, as well as to produce a narrow space between the two chambers, and to form a central branch for attachment to the carburettor, substantially 10 as set forth.

15 In testimony whereof I have signed my name to this specification.

JOHN DAVENPORT SIDDELEY.
